P. HUTTLIN

BOUNCE BALL GAME APPARATUS

Filed July 3, 1924

UNITED STATES PATENT OFFICE.

PAUL HUTTLIN, OF GERMANTOWN, PENNSYLVANIA, ASSIGNOR OF ONE-HALF TO
ROSS B. LINTON, OF PHILADELPHIA, PENNSYLVANIA.

BOUNCE-BALL GAME APPARATUS.

Application filed July 3, 1924. Serial No. 723,886.

To all whom it may concern:

Be it known that I, PAUL HUTTLIN, a citizen of the United States, residing at Germantown, county of Philadelphia, State 5 of Pennsylvania, have invented a new and useful Bounce-Ball Game Apparatus, of which the following is a specification.

My invention relates to a novel construction of a bounce ball game apparatus, 10 wherein I employ an inclined, preferably rectangular box divided by partitions, preferably arranged at right angles, so as to form a plurality of numbered compartments, which are adapted to receive balls, 15 which are caused to bounce into the compartments so numbered from a prescribed distance, means being provided for forming a back stop whose lower horizontal portion forms the rear wall of the box, so that a rigid and durable construction, is provided, 20 whereby any misdisplayed balls, bouncing over or beyond the compartments will tend to be deflected by the said back stop into one of the compartments.

25 The entire apparatus is supported on two front legs and two rear legs, which depend from the lower portion of the back stop frame, said latter legs being spaced wider apart than the front legs, so that the apparatus is at all times rigidly supported, and can be readily transported as a unit to and from the place of use, as picnics, carnivals and the like.

30 By my device a novel bounce ball game apparatus is provided, which is simple, durable and inexpensive to construct, and which will afford considerable amusement and require considerable skill to play.

35 It further consists of other novel features of construction and advantage, all as will be hereinafter fully described and pointed out in the claims.

40 For the purpose of illustrating my invention I have shown in the accompanying drawings forms thereof which are at present preferred by me, since the same have been found in practice to give satisfactory and reliable results, although it is to be understood that the various instrumentalities 45 of which my invention consists can be variously arranged and organized and that my invention is not limited to the precise arrangement and organization of the instrumentalities as herein shown and described.

50 Figure 1 represents a perspective view of

a novel bounce ball game apparatus embodying my invention.

Figure 2 represents a vertical sectional view on line 2—2 Figure 1.

Figure 3 represents a plan view of the 60 rear wall of the apparatus which also forms the bottom of the back stop frame.

Similar numerals of reference indicate corresponding parts.

1 designates my novel construction of a 65 bounce ball game apparatus, the same comprising a base member 2 having the sides 3, the front wall 4 and the rear wall 5 which is provided with laterally extending terminal arms 6, which are mortised, screwed or otherwise secured to the upright rear legs 7, which are joined at their upper portions by the upper bar or rail 8. The space between the legs 7, the top rail 8 and the lower back member 5 is provided with a back stop 9 70 of board or of wire mesh or the like. 10 designates the transverse partitions, which in the present instance are two in number. 11 designates the longitudinally extending 75 partitions which are three in number, whereby a series of compartments 13 is formed, which are numbered 1 to 12, as will be understood from Figure 1. The front of the apparatus is supported by the front legs 12, 80 which are closer together than the rear legs 7, so that the apparatus is effectively supported under all conditions and can be readily transported or set up at any desired point.

85 The manner of constructing and locating 90 the back stop, adds greatly to the rigidity of the device, and by projecting the back stop up to about the height shown in Figure 1, any misdisplayed balls hitting the back stop 95 will tend to be projected therefrom into the various pockets or compartments.

In playing the game the players employ 100 preferably soft rubber balls, each player being given a predetermined number of balls and the game is played by each player lodging his ball in a compartment on the first bounce. The game can be played by two or more persons, individually or in teams, setting a goal number to be obtained, the winner being the person or team that attain the 105 goal number first. The game can also be played by individuals or teams totaling the numbers of the compartments after all balls assigned to player or team receiving the highest total is the winner of the game. 110

It will now be apparent that I have devised a novel and useful bounce ball game apparatus which embodies the features of advantage enumerated as desirable in the statement of the invention and the above description, and while I have, in the present instance shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letter Patent, is:

1. In a game apparatus, an inclined bottom, front and side walls therefor, a back stop, a rear wall forming both the rear

wall of the apparatus and the bottom of the back stop and provided with laterally extending arms projecting beyond said side walls, upright rear legs attached to said arms, a top rail attached to the upper portions of said rear legs and a back stop intermediate said rear legs, back wall and top rail.

2. In a game apparatus, an inclined bottom, front and side walls therefor, a back stop, a rear wall forming both the rear wall of the apparatus and the bottom of the back stop and provided with laterally extending arms, upright rear legs attached to said arms, a top rail attached to the upper portions of said upright legs, a back stop intermediate said rear legs, back wall, and top rail, and a pair of front legs which are spaced closer together than said rear legs.

PAUL HUTTLIN.
